CLAIM

The ornamental design for a bridge for eyeglasses, as shown and described.

DESCRIPTION

FIG. 1 is a top plan view of the bridge for eyeglasses showing my new design, the bottom view being a mirror image thereof;

FIG. 2 is a front elevational view thereof;

FIG. 3 is a rear perspective view thereof with a portion of an eyeglass frame shown in broken lines for illustrative purposes only; and

FIG. 4 is a side elevational view thereof, the opposite side being a mirror image thereof.
